UNITED STATES PATENT OFFICE.

HENRY LLEWELYN KINGSMILL, OF PRESTON, ENGLAND.

APPARATUS FOR DARNING WOVEN OR KNITTED ARTICLES OR FABRICS.

Application filed February 9, 1923. Serial No. 618,143.

To all whom it may concern:

Be it known that I, HENRY LLEWELYN KINGSMILL, a subject of the King of England, and residing at Preston, Lancashire, in England, have invented certain new and useful Improvements in Apparatus for Darning Woven or Knitted Articles or Fabrics, of which the following is a specification.

10 This invention relates to apparatus for darning knitted or woven fabrics or articles of the kind in which the fabric to be darned is gripped between a pair of diagonally corrugated plates which have parallel 15 grooves intersecting the corrugations so as to form a series of passages between the plates for a reciprocating needle.

The object of this invention is to provide an apparatus which is of simple and compact construction and adapted to darn the fabric or article in a manner which will permit of shrinkage when the article is subsequently washed.

To this end according to this invention 25 the corrugated plates constituting the work table are mounted to slide in straight guides formed in the bed or base of the apparatus and a needle carrying member is provided adapted to reciprocate in a path at right 30 angles to the movement of the work table. The needle is adapted to carry loops of thread or the like through the needle passages in the work table and means are provided for preventing the loops thus carried 35 through from being withdrawn with the needle as well as for advancing the work table step by step along its guides.

Further, to prevent the darning threads being drawn too tightly and to ensure the 40 formation of loops of sufficient dimensions to permit shrinkage when the article is subsequently washed, pins or pegs are provided on the work table around which each loop is caused to pass before being engaged in 45 the known manner by the next succeeding loop so that although a chain of loops is formed, there is considerable play or looseness at the end of each darning thread.

In the preferred construction the apparatus 50 comprises a base or bed formed oval or ovoid in plan and supporting in suitable bearings a rod adapted to carry a needle at one end and provided with an operating handle on the other end by which the rod 55 can be reciprocated. Formed at right angles to the rod in the upper face of the base, are

guides for the work-supporting table, the guides being conveniently undercut. The under surface of the lower plate carries a rack with which a pawl mounted on the 60 base and operated by the return movement of the rod engages. Thus the work table is moved in a path at right angles to that of the rod each time the latter is reciprocated and is directly operated by the needle 65 rod.

In addition to a thread catching device of known construction, a spring finger or the like is secured to the bed so as to bear against the edge of the table, this finger 70 not only preventing withdrawal of the loop, after the thread catcher has become disengaged therefrom but further, when the table advances, holding the loop last made in the path of the needle and over the end of the 75 next following groove in the table. Further a row of upwardly projecting pins or pegs is formed along the longitudinal edge of the table around which the thread is forced to pass between the formation of each loop, 80 thus preventing the loops being drawn too tightly. When the needle next emerges from the table the loop so formed is threaded through the one previously formed and held by the spring finger a chain of loops 85 being thus produced. The final loop may be finished by hand or tied in some other suitable manner to prevent unravelling of the chain.

A preferred construction according to this 90 invention is illustrated in the accompanying drawings in which:—

Figure 1 is a sectional side elevation.

Figure 2 is a plan.

Figure 3 is an inverted plan, part of the 95 operating rod being broken away.

Figure 4 is a plan on an enlarged scale showing the work-carrying table, a portion of the upper corrugated plate being broken away.

Figure 5 is a side elevation of the work-carrying table, and

Figure 6 is a detail view showing in perspective the sear pipe and the portion of the rod cooperating therewith.

In the construction illustrated the apparatus comprises a base or bed A having a downwardly inclined flange A' constituting a supporting foot. Formed at right angles to the major axis of the bed, which is ovoid 110 in plan, is an undercut groove or recess constituting a guide B for a work-supporting

table hereafter more fully described. The flange A' is drilled or bushed at each end to receive and support an operating rod C which can be reciprocated in a direction 5 parallel to the length of the bed by means of an operating handle C', a lug or standard C² secured to the rod projecting upwards through a slot A² in the bed and preventing rotary motion of the rod when it is reciprocated. The lug C² is provided with an adjustable tension spring C³ and means for carrying a needle D such for example as a set screw D'. The needle may be of the known sewing machine type and lies in a 10 plane parallel to the surface of the bed.

The work-supporting table comprises a pair of plates E F having ribs E' F' of V-section disposed at an angle of 45° to the sides of the plates formed on one face thereof. These ribs constitute a series of diagonal corrugations and each of the plates is provided with a series of parallel grooves E² F² which intersect the corrugations and lie at right angles to the length of the table 20 and of the operating rod. The grooves E² F² constitute a series of passages through which the needle D can be successively passed in a manner hereafter described.

The lower plate F is shaped to fit the 30 undercut groove B and carries on its under surface a toothed rack G adapted to co-operate with feed mechanism actuated by the rod C in such a way that when the rod is reciprocated the work-supporting table 35 is caused to move in a path at right angles to the needle by mechanism hereafter more fully described.

The lower plate F further carries upwardly projecting standards F³ which are 40 slotted to receive some suitable spring clamp or the like H by means of which the two plates E and F are pressed together and thus made to grip the woven or knitted fabric which is placed between them.

45 Mounted on the upper surface of the bed plate A is a thread-catching device comprising a hook member J keyed to a spring-controlled spindle J' the lower end of which is secured to a lever J² lying between the 50 rod C and the under surface of the base plate. The free end of the lever J² carries a stud or projection J³ with which a leaf spring or finger K connected to the rod C engages towards the end of the outward 55 stroke and during the early part of the return stroke of the rod. Cooperation between the spring finger K and the lever J² is effected by means of a sear member or 60 ramp L secured to the under surface of the base plate and comprising an inclined portion L' and a flat step L² separated by a gap L³ shown in Figure 6.

65 Normally the spring surrounding the spindle J' causes the hook member J to lie across the path of the needle. When however the

rod C nears the end of its forward stroke, the inclined surface L' deflects the spring finger upwards so that its forward edge engages the stud J³ on the lever J². Continued movement of the rod rocks the lever 70 J² and therefore the hook J against the action of its spring out of the path of the needle into the position shown in Figure 2. The step L² on the sear member retains the finger K in engagement with the stud until, 75 just as the needle is being drawn back between the plates E and F the return movement of the rod carries the end of the finger over the gap L³. The finger falls into the gap and passing below the inclined ramp L' releases the pin J³ whereupon the hook is returned by its spring to its normal position, the inclined surface L' retaining the finger in its depressed or inoperative position.

85 The feed mechanism for the work-carrying table comprises a pawl M pivoted to the underside of the base plate and having a tongue piece G' adapted to engage the teeth of the rack G. The pawl is normally held by a spring M' against a stop M² and at its free end has an inclined nose M³ and a cam surface M⁴.

90 The pawl is operated by a yielding pin N carried by the rod, the arrangement being 95 such that, when the rod advances, the pin N is depressed by engagement with the nose M³ and therefore during the forward stroke of the rod is inoperative. Towards the end of the return stroke however, the pin N engages the cam surface M⁴ and thus rocks the pawl M against its spring, thereby moving the work table within its guides B owing to the engagement of the tongue G' with the 100 rack G. A spring M⁵ (which may be adjustable) engages the ratchet G and ensures that the correct travel is imparted to the table at each reciprocation of the rod C.

105 Not only is a thread-catching device required but, in addition, a retaining device, which will hold the loop after the hook has become disengaged therefrom and during the movement of the table. In the construction shown this comprises a spring finger O mounted on the base plate and adapted not only to prevent the loop of thread being unintentionally withdrawn but also to hold in the path of the needle the loop formed by one reciprocation of the rod during the next 110 stroke of the rod so that each loop is threaded through the one formed immediately before it and the series of loops thus constitute a chain. To prevent the threads or loops being drawn too tight and to allow for shrinkage, pins such as P are formed 115 along the sides of the lower plate F around which the threads pass.

120 The operation of the apparatus is as follows:—

125 The fabric to be darned is clamped be-

tween the plates E, F by the spring H and a darning thread is passed under the tension spring C³ and threaded through the eye of the needle D. The work-carrying table is then so placed within its guides B that the extreme left-hand groove E², F² (i. e. the uppermost groove in the figure) is in alignment with the needle.

The rod C is then pushed forwards into the position shown in the drawings whereupon the thread is carried by the needle through the raised portions of the fabric gripped between the corrugated plates. Just before the needle emerges from between the far edges of the plates, the hook J is swung clear of the needle into the position shown in Figure 2 by the finger K engaging the stud J³. This finger remains in contact with the stud until, on the return of the rod, the finger is drawn off the flat surface L² and enters the gap L³ whereupon the stud J³ is released and the hook, under the action of its spring, is caused to fly back, thus catching the loop of thread formed below the needle. The continued return movement of the rod actuates the pawl M through the spring-controlled finger N and cam surface M⁴ thus advancing the work table directly the needle is clear thereof.

When the work-carrying table is moved within its guides the loop of thread which has been caught by the hook J is drawn under the spring finger O and thereby pressed against the edge of the table. Not only is this loop thus gripped against unintentional withdrawal but further, owing to the movement of the table, the end of the loop is brought over the end of the next groove so that when the needle next emerges towards the end of its next stroke it necessarily passes through the loop thus made the thread from which the next loop is formed. In this manner as the table is advanced step by step a chain or series of loops is formed and this is prevented from becoming unravelled by the last thread being finished off by hand in some suitable manner.

To prevent the loops being drawn too tightly and to allow for shrinkage the upwardly projecting pins P are provided around which the thread is forced to pass between the formation of each loop.

What I claim as my invention and desire to secure by Letters Patent is:—

1. In apparatus for darning woven or knitted fabrics the combination of a bed plate, a work table comprising a pair of diagonally corrugated plates between which the fabric is gripped, having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides, means for holding each loop carried through a needle passage in the path of the next following loop when the table advances as set forth. 125

member adapted to carry loops of thread successively through the needle passages in the work table, and means actuated by the reciprocating member for advancing the work table step by step along its guides as set forth. 70

2. In apparatus for darning woven or knitted fabrics the combination of a bed plate, a work table comprising a pair of diagonally corrugated plates between which the fabric is gripped having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides and means for holding each loop carried through a needle passage in the path of the next following loop when the table advances as set forth. 90

3. In apparatus for darning woven or knitted fabrics the combination of a bed plate, a work table comprising a pair of diagonally corrugated plates between which the fabric is gripped having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides and means for holding each loop carried through a needle passage in the path of the next following loop when the table advances as set forth. 95

4. In apparatus for darning woven or knitted fabrics the combination of a bed plate, a work table comprising a pair of diagonally corrugated plates between which the fabric is gripped having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides and pins on the work table adapted to engage the loops formed by the needle as set forth. 100

4. In apparatus for darning woven or knitted fabrics the combination of a bed plate, a work table comprising a pair of diagonally corrugated plates between which the fabric is gripped having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides and pins on the work table round which each loop passes before being engaged by the next following loop as set forth. 110

5. In apparatus for darning woven or knitted fabrics the combination of a bed plate, a work table comprising a pair of diagonally corrugated plates between which the fabric is gripped, having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides, means for holding each loop carried through a needle passage in the path of the next following loop when the table advances as set forth. 115

6. In apparatus for darning woven or knitted fabrics the combination of a bed plate, a work table comprising a pair of diagonally corrugated plates between which the fabric is gripped, having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides, means for holding each loop carried through a needle passage in the path of the next following loop when the table advances as set forth. 120

7. In apparatus for darning woven or knitted fabrics the combination of a bed plate, a work table comprising a pair of diagonally corrugated plates between which the fabric is gripped, having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides, means for holding each loop carried through a needle passage in the path of the next following loop when the table advances as set forth. 125

8. In apparatus for darning woven or knitted fabrics the combination of a bed plate, a work table comprising a pair of diagonally corrugated plates between which the fabric is gripped, having needle passages formed therein, straight guides formed in the bed plate in which the work table slides, a reciprocating member mounted in the bed plate and adapted to move in a path at right angles to that of the work table, a needle carried by the reciprocating member adapted to carry loops of thread successively through the needle passages in the work table, means actuated by the reciprocating member for advancing the work table step by step along its guides, means for holding each loop carried through a needle passage in the path of the next following loop when the table advances as set forth. 130

5. In apparatus for darning woven or knitted fabrics the combination of a flanged bed plate having an undercut transverse groove formed in its upper surface, a work table comprising two superimposed corrugated plates one of which slides within the groove, these plates having needle passages formed therein, a spring member tending to press the corrugated plates together, 10 a reciprocating member mounted in sockets in the flanged portion of the bed plate and adapted to move in a path at right angles to that of the work table, a needle mounted on the reciprocating member adapted to carry 15 loops of thread through the needle passages in the work table, a thread catcher adapted to hold such loops when the needle is withdrawn, a spring finger adapted to hold each loop in the path of the next following loop 20 and automatic mechanism directly operated by the reciprocating member for moving the work table step by step along the groove as set forth.

6. In apparatus for darning woven and 25 knitted fabrics the combination of a bed

plate, a work table comprising a pair of diagonally corrugated plates between which the fabric is gripped having needle passages formed therein, straight guides formed in the bed plate in which the work table slides, 30 a reciprocating member mounted in the bed plate and adapted to move in a path at right angles to that of the work table, a needle carried by the reciprocating member adapted to carry loops of thread successively 35 through the needle passages in the work table and means actuated by the reciprocating member for advancing the work table step by step along its guides, such means comprising a pivot, a rack on the work table, 40 a pawl on one end of the pivot engaging the rack, a lever on the other end of the pivot, a ramp on the lever and a pin mounted on the reciprocating member adapted to engage the ramp so as to move the lever, and thus rotate the pivot and advance the work table 45 as set forth.

In testimony whereof I have signed my name to this specification.

HENRY LLEWELYN KINGSMILL.
